CODED TRACK CIRCUITS

Herman G. Blosser, Pittsburgh, Pa., assignor to
 The Union Switch & Signal Company, Swiss-
 vale, Pa., a corporation of Pennsylvania

Application September 28, 1943, Serial No. 504,133

5. Claims. (Cl. 246—38)

My invention relates to a railway signaling system of the coded track circuit type in which impulses of feed back energy are supplied to the section rails at the entrance end thereof in the intervals between impulses of master code and operate a detector relay at the exit end of the section to indicate occupancy of the track section at that point.

In some situations it is desirable to divide a track section into two subsections and to employ the track relay of the forward subsection to control the supply of coded energy to the rails of the rearward subsection. In order to equalize the "on" and "off" periods in the coded energy supplied to the rails of the rearward subsection it may be desired to arrange the apparatus so that energy is supplied to the rails of the rearward subsection over a circuit including a back contact of the track relay for the forward subsection.

Where a feed back detector relay of the polar stick type is employed the equipment is arranged so that this relay is connected across the section rails during the "off" periods in the coded energy supplied to the section rails so that energy supplied over the section rails will move the relay contacts to one position, while means is provided to supply energy to the relay during the "on" periods in the coded energy supplied to the section rails to move the relay contact to its other position.

As explained in application Serial No. 473,792 of C. E. Staples and myself there is a short time interval from the instant the supply of master code to the section rails is cut off until feed back energy is supplied over the section rails and operates the detector relay contacts. If energy is supplied to the detector relay at the start of each "on" period in the code supplied to the section rails the contacts of the detector relay will occupy the position to which they are moved by feed back energy a substantially smaller proportion of the time than they occupy the other one of their two positions. This reduction in the time that the detector relay contacts occupy the position to which they are moved by feed back energy necessitates the use of an approach relay having a low resistance winding, while the use of a relay with a low resistance winding increases the energy consumed by this relay and increases wear on the contact of the detector relay which controls the circuit of the approach relay. In addition, if the time that the detector relay contacts occupy the position to which they are moved by feed back energy is reduced, the periods during which the supply of energy to the approach

relay is interrupted are correspondingly increased and the release time of this relay must be increased to insure that the relay will remain picked up during the periods in which the circuit of the relay is interrupted. Accordingly, the period which must elapse after a train enters the section before the approach relay releases is increased, and if the approach relay is employed to control the supply of cab signal control energy to the section rails this delay in the release of the approach relay may be objectionable.

Similarly, if a feed back detector relay of the polar biased neutral type is employed, the relay is provided with a holding winding to which energy is supplied after the relay contacts pick up, and which serves to hold the relay contacts picked up throughout the "off" periods in the code supplied to the section with which the relay is associated. If the supply of energy to this holding winding is interrupted at the start of each "on" period in the code, the contacts of the detector relay will be picked up for substantially less than one half of the time and the time during which energy is supplied to the approach relay is correspondingly reduced and the operating difficulties described above are encountered with the approach relay.

It is an object of this invention to provide improved means for use at a cut section where back contact coding is employed to control the supply of energy to the detector relay for the rearward subsection so that movement of the relay contacts is delayed substantially as long at the start of an "on" period in the code supplied to the section rails as movement of the relay contacts is delayed at the start of an "off" period in the code.

A further object of the invention is to provide improved apparatus of the type described employing a feed back detector relay of the polar stick type and incorporating means for delaying the supply of energy to the relay at the start of each "on" period in the code to thereby delay response of the relay at these times.

Another object of the invention is to provide improved apparatus of the type described employing a feed back detector relay of the polar biased neutral type and incorporating means for delaying interruption of the holding circuit for the relay at the start of each "on" period in the code to thereby delay release of the relay at such times.

Other objects of the invention and features of novelty will be apparent from the following de-

scription taken in connection with the accompanying drawing.

I shall describe two forms of coded track circuit apparatus embodying my invention and shall then point out the novel features thereof in claims.

In the drawing

Fig. 1 is a diagram of a section of railway track equipped with track circuit apparatus employing feed back detector relays of the polar stick type and having the equipment at the cut section arranged as taught by this invention, and

Fig. 2 is a fragmentary view showing how the cut section apparatus may be arranged where a feed back detector relay of the polar biased neutral type is employed.

Similar reference characters refer to similar parts in each of the two views.

In practicing my invention I employ a contact of the impulse relay which controls the supply of feed back energy to the rails of the forward subsection to control the circuit of the detector relay for the rearward subsection, instead of employing a contact of the track relay for this purpose as heretofore. On release of the track relay there is a short time interval until the contacts of the impulse relay pick up and this time interval is substantially as long as the period from picking up of the track relay contacts until response of the detector relay to feed back energy supplied over the section rails so that this arrangement operates to substantially equalize the periods during which the detector relay contacts occupy each of their two positions.

Referring to Fig. 1 of the drawing there is shown therein a section of railway track through which traffic normally moves in the direction indicated by the arrow, that is from left to right. The track rails 1 and 2 are divided by insulated joints 3 into track sections, while the rails of the track section shown in the drawing are divided by insulated joints 3 into a first or forward subsection A2T and a second or rearward subsection B2T. Each of these subsections is provided with track circuit apparatus of the type employing coded energy, while the track circuit apparatus for each subsection includes means for supplying coded alternating current to the section rails when the section is occupied to operate cab signal apparatus on a locomotive present in the section.

This invention is directed particularly to the apparatus at the junction between the sections A2T and B2T, and the equipment at the exit end of section A2T and at the entrance end of section B2T may be arranged in any appropriate manner well-known in the art. In the drawing the equipment at the exit end of section A2T is arranged as shown in the above identified application of C. E. Staples and myself, while the equipment at the entrance end of section B2T is arranged as shown in United States Patent 2,286,002 to F. H. Nicholson.

Each track section is provided with a code following track relay TR of the polar biased neutral type connected across the section rails at the entrance end of the section, and a feed back detector relay K of the polar stick type connected across the section rails at the exit end of the section. The supply of master code energy to the rails of the forward subsection is controlled by a coding relay CR, while the coding relay CR is operated at one or another of a plurality of different rates governed by traffic conditions in advance.

Each location in the track stretch is provided with a suitable source of direct current, such as a storage battery, not shown, the terminals of which are designated B and C in the drawing, 5 while the alternating current cab signal control energy is supplied from a suitable source, not shown, the terminals of which are designated BX and CX in the drawing.

The equipment is shown in the condition which 10 it assumes when the track section is vacant. When the contacts of coding relay CR are picked up its contact 10 interrupts the circuit of the track winding 11 of detector relay A2K and connects the track battery A2TB and the track transformer A2TT across the section rails. At this time energy flows from the positive terminal of the battery A2TB to track rail 1, through the winding of track relay A2TR from left to right, over back contact 12 of relay A2IR, track rail 15 2 and front contact 10 of relay CR to the negative terminal of the battery. In addition, when the contacts of relay CR are picked up contact 14 20 establishes the circuit of the local winding 15 of relay A2K and causes the contact 16 of this relay to move to its right hand or reverse position in which it interrupts the circuit of approach relay A2AP.

The energy supplied from the track battery A2TB picks up the contacts of track relay A2TR 30 with the result that contact 18 of relay A2TR connects the track winding 19 of detector relay B2K across the rails of section B2T and interrupts the circuit for supplying energy from the track battery B2TB to the rails of section B2T.

As the supply of energy from the track battery B2TB to the rails of section B2T is cut off the contacts of track relay B2TR are released, 35 while on release of the contacts of relay B2TR an impulse of energy is supplied from the decoding transformer B2DT to the impulse relay B2IR and picks up the contacts of relay B2IR momentarily to cause an impulse of energy to be supplied from the battery B2FB to the detector relay B2K over the circuit which is traced from the 40 positive terminal of the battery B2FB over front contact 20 of relay B2IR, winding of relay B2TR from right to left, track rail 1, winding 19 of relay B2K, front contact 18 of track relay A2TR, and track rail 2 to the negative terminal of the battery B2FB. The energy supplied from the battery B2FB to relay B2K moves the contact 22 of relay B2K to its left hand or normal position in which it establishes the circuit of approach relay B2AP, 45 while the operating characteristics of the relay B2K are such that the relay contact remains in its normal position after the contact 20 of relay B2IR releases and cuts off the supply of energy from the battery B2IR.

The energy supplied to relay B2AP over normal polar contact 22 of relay B2K picks up contact 23 of relay B2AP to prevent the supply of energy to the primary winding of transformer B2TT and to short circuit this winding to minimize arcing at back contact 18 of the track relay 60 A2TR.

On release of the contacts of coding relay CR, 65 contact 14 interrupts the circuit of the local winding 15 of relay A2K, while contact 10 of relay CR interrupts the circuit of the track battery A2TB and connects the track winding 11 of relay A2K across the rails of section A2T. On interruption of the supply of energy from the track battery A2TB to the rails of section A2T the contacts of the track relay A2TR release so 70 that contact 18 interrupts the circuit of the track 75 relay A2TR.

winding 19 of relay B2K and connects the track battery B2TB across the rails of section B2T so that energy from battery B2TB feeds to track relay B2TR and picks up its contacts. On picking up of the contacts of the track relay B2TR an impulse of energy is supplied from transformer B2DT to relay B2IR but the polarity of this impulse is such that it is ineffective to pick up the contacts of relay B2IR.

In addition on release of the contacts of relay A2TR an impulse of energy is supplied from the decoding transformer A2DT to the impulse relay A2IR to pick up its contacts momentarily. On picking up of relay A2IR its contact 12 connects battery A2FB across the rails of section A2T and energy is supplied from this battery to relay A2K over the circuit which is traced from the positive terminal of the battery through the winding of track relay A2TR from right to left, track rail 1, track winding 11 of relay A2K, back contact 10 of relay CR, and track rail 2 to the negative terminal of the battery. The energy supplied from the battery A2FB to the relay A2K moves the contact 16 of this relay to its left hand or normal position in which it establishes the circuit of relay B2AP, while the contact 16 remains in its normal position after relay A2IR releases and cuts off the supply of energy from the battery A2FB to relay A2K. The energy supplied over contact 16 of relay A2K to relay A2AP picks up the contacts 25 of this relay to thereby prevent the supply of energy to the primary winding of transformer A2TT and to short circuit this winding to reduce arcing at front contact 10 of relay CR. The relay A2AP is of a type the contact of which is slow to release so that the relay contact remains picked up during the periods in which the contact 16 of relay A2K is normally in its reverse position.

On picking up of the contacts of relay A2IR its contact 26 establishes the circuit of the local winding 28 of relay B2K and causes the contact 22 of relay B2K to move to its right hand or reverse position in which it interrupts the circuit of the relay B2AP. The supply of energy to winding 28 of relay B2K is interrupted as soon as relay A2IR releases, but the contact 22 of relay B2K will move to its reverse position before relay A2IR releases and will remain in its reverse position after relay A2IR releases.

During the next picked up period of the contacts of the coding relay CR energy is supplied to the local winding of relay A2K, and is supplied from track battery A2TB over the rails of section A2T to the track relay A2TR and picks up its contacts to interrupt the supply of energy from track battery B2TB to the track relay B2TR and to connect the track winding 19 of relay B2K across the rails of section B2T. On release of the track relay B2TR the relay B2IR picks up to supply an impulse of feed back energy from battery B2FB to relay B2K to move its contact 22 to its normal position in which it establishes the circuit of relay B2AP.

As a result of code following operation of the track relays B2TR and A2TR energy is supplied through the decoding transformers B2DT and A2DT to the relays B2H and A2H to keep their contacts picked up. Similarly, as long as the section is vacant, the contacts of the detector relays B2K and A2K are moved to their reverse position during each "on" period in the code supplied to the associated section, and are moved to their normal positions by feed back energy

supplied over the section rails during each "off" period in the code.

As pointed out above, on picking up of the contacts of track relay A2TR the circuit of the track battery B2TB is interrupted and the track winding 19 of relay B2K is connected across the rails of section B2T. On interruption of the circuit of the track battery B2TB the track relay B2TR releases so that energy is supplied through the decoding transformer B2DT to relay B2IR and its contacts pick up to cause energy to be supplied from battery B2FB to relay B2K to move contact 22 to its left hand or normal position in which it establishes the circuit of relay B2AP. It will be seen that some time elapses from the instant the contacts of track relay A2TR pick up to start the "off" period in the code supplied to section B2T, and the instant at which feed back energy supplied over the section rails moves the contact of relay B2K to its normal position to establish the circuit of relay B2AP.

The apparatus provided by this invention is arranged so that on release of the track relay A2TR to initiate an "on" period in the code supplied to section B2T, energy is not supplied to the local winding 28 of relay B2K immediately. Instead, the supply of energy to this winding is delayed until the relay A2IR picks up, and this does not occur for an appreciable time interval subsequent to release of the contacts of the track relay A2TR. Accordingly, contact 22 of relay B2K remains in its left hand or normal position and maintains the circuit of the relay B2AP for a period subsequent to the start of an "on" period in the code supplied to section B2TR. The delay in the supply of energy to the local winding of relay B2K after release of track relay A2TR to initiate an "on" period in the code supplied to section B2T is almost as long as the delay in the supply of feed back energy to the relay B2K after picking up of the track relay A2TR to initiate an "off" period in the code supplied to section B2T. This delay in the supply of energy to relay B2K on release of the track relay A2TR substantially increases the length of the periods during which contact 22 of relay B2K establishes the circuit of relay B2AP and correspondingly decreases the periods during which the circuit of relay B2AP is interrupted.

This increase in the proportion of the time that energy is supplied to the relay B2AP, and the decrease in the length of the periods during which the relay contacts must remain picked up while the supply of energy to the relay winding is interrupted, makes possible the use of a relay with a much higher resistance winding than would otherwise be required. The high resistance relay which this invention makes it possible to use consumes less energy than would be required by a lower resistance relay, while the decrease in the energy in the circuit of the relay results in less wear on the contact 22 of relay B2K controlling this circuit.

The reduction in the release time of the relay B2AP made possible by the reduction in the length of the periods during which the relay contacts must remain picked up results in more prompt release of the relay when a train enters the track section.

Where a train moving in the normal direction of traffic enters section B2T the track relay B2TR is shunted and ceases to follow code so relay B2H releases, while relay B2IR remains released and feed back energy is no longer supplied to the section rails. Accordingly, contact 22 of relay

B2K is not moved to its normal position to establish the circuit of relay B2AP, but remains in its reverse position in which it interrupts the circuit of this relay, and after a short period contact 23 of relay B2AP releases and establishes the circuit of the primary winding of track transformer B2TT so that on continued operation of the track relay A2TR coded alternating current is supplied to the rails of section B2T to operate the cab signal apparatus on the locomotive in that section.

When the train advances into section A2T the track relay A2TR ceases to follow code and relay A2H releases and its contact interrupts the circuit of the track battery B2TB and of the track transformer B2TT to thereby cut off the supply of energy to section B2T. In addition, at this time relay A2IR remains released so energy is no longer supplied from battery A2FB to relay A2K and its contact 16 remains in its reverse position in which it interrupts the circuit of relay A2AP. Accordingly, relay A2AP releases and its contact 25 establishes the circuit of the primary winding of transformer A2TT so that on continued operation of coding relay CR coded alternating current is supplied to the rails of section A2T to operate the cab signal apparatus on the locomotive while it is in that section.

When section A2T is vacated coded energy again feeds to track relay A2TR and operates it so that relay A2H is picked up and establishes the circuit of the track battery B2TB so that energy from this battery is supplied to track relay B2TR. As a result of operation of the track relays the impulse relays operate to supply feed back energy to the section rails to cause the detector relays to establish the circuits of the approach relays so that the contacts of the approach relays pick up and cut off the supply of energy to the track transformers.

In Fig. 2 there is shown cut section apparatus employing a feed back detector relay B2KA of the biased polar neutral type. The relay B2KA is arranged so that its contacts pick up only when energy flows through the relay from left to right, while the approach relay B2AP is energized in series with the local or holding winding 28 of relay B2KA over a circuit which includes front contact 22 of relay B2KA and back contact 26 of relay A2IR. The modification shown in Fig. 2 is otherwise the same as that shown in Fig. 1.

When the track relay A2TR is picked up its contact 18 interrupts the circuit of track battery B2TB and connects the track winding 19 of relay B2KA across the rails of section B2T. During this "off" period in the code supplied to section B2T the equipment at the entrance end of this section operates as explained in connection with Fig. 1 to supply an impulse of feed back energy over the section rails to relay B2KA and its contact 22 picks up and establishes the circuit including back contact 26 of relay A2IR for energizing the holding winding 28 of relay B2KA and the winding of relay B2AP in series. The energy supplied to winding 28 of relay B2KA keeps the contact of this relay picked up while the energy supplied to relay B2AP holds its contact 23 picked up so that energy is not supplied to the primary winding of transformer B2TT.

On release of the contacts of track relay A2TR contact 18 interrupts the circuit of the track winding 19 of relay B2KA and connects the track battery B2TB across the rails of section B2T. In addition, on release of the contacts of track relay A2TR an impulse of energy is sup-

plied through the transformer A2DT to relay A2IR to pick up its contacts momentarily and cause an impulse of feed back energy to be supplied to the rails of section A2T. Also on picking up of relay A2IR its contact 26 interrupts the circuit for energizing the relay B2AP and the holding winding 28 of relay B2KA in series and contact 22 of relay B2KA releases to additionally interrupt this circuit and prevent it from being reestablished on release of relay A2IR. At this time, therefore, the supply of energy to the winding of relay B2AP is cut off, but because of the slow releasing characteristics of the relay, its contact 23 remains picked up and interrupts the circuit of transformer B2TT.

On the next movement of the contacts of track relay A2TR to their picked up position contact 18 cuts off the supply of energy from battery B2TB to the rails of section B2T and connects the track winding 19 of relay B2KA across the rails of section B2T so that feed back energy supplied to the section rails at the entrance end of the section feeds to the relay B2KA and its contact 22 picks up to establish the circuit for energizing the relay B2AP and the holding winding 28 of relay B2KA in series. The energy supplied over this circuit keeps the contact 22 of relay B2KA picked up to maintain the circuit, while this energy also maintains the relay B2AP picked up.

On subsequent release of the contacts of the track relay A2TR the circuit of relay B2AP is not interrupted until relay A2IR picks up, and, as pointed out in connection with the modification shown in Fig. 1, relay A2IR does not pick up for an appreciable time interval after the contacts of the track relay A2TR release. Accordingly, the circuit of relay B2AP is maintained somewhat longer than it would be maintained if the circuit of this relay were controlled by the track relay instead of by the impulse relay.

The increase which the circuit produces in the length of the periods during which energy is supplied to the relay B2AP, and the corresponding decrease in the length of the periods during which the contacts of the relay must remain picked up while the supply of energy to the relay is interrupted, makes possible the use of a relay with a higher resistance winding than would otherwise be required. As explained in connection with Fig. 1 this results in a reduction in the current consumed by this relay and a reduction in the wear on contact 22 of relay B2K controlling the circuit of relay B2AP.

When a train enters section B2T the supply of feed back energy over the section rails is cut off and the contact of relay B2KA remains released and does not establish the circuit of the relay B2AP and after a short period its contact 23 releases and establishes the circuit of the track transformer so that coded alternating current is supplied to the rails of section B2T.

Although I have herein shown and described only two forms of coded track circuit apparatus embodying my invention, it is understood that various changes and modifications may be made therein within the scope of the appended claims without departing from the spirit and scope of my invention.

Having thus described my invention, what I claim is:

1. In combination, a stretch of railway track including adjacent first and second track sections, said first track section being equipped with coded track circuit apparatus including a code

following track relay having associated therewith an impulse relay having normally released contacts movable to a picked up position in which they establish a circuit to supply energy to the rails of said first section, means responsive to release of the track relay contacts for supplying to said impulse relay energy effective to pick up the relay contacts momentarily, means including a back contact of said track relay for supplying energy to the rails of said second section, means including a front contact of said track relay for connecting a winding of a code following detector relay across the rails of said second section, said second section being equipped with track circuit apparatus effective when the section is vacant to supply to said detector relay over the section rails in the periods in which the detector relay is connected across the section rails energy to move the detector relay contacts from their first to their second position, an approach relay, a circuit governed by a contact of said detector relay for supplying energy to said approach relay, and a circuit controlled by a contact of said impulse relay for supplying energy to said detector relay to thereby maintain the detector relay contacts in their second position until the impulse relay contacts pick up and to thereafter cause the detector relay contacts to move from their second to their first position.

2. In combination, a stretch of railway track including adjacent first and second track sections, said first track section being equipped with coded track circuit apparatus including a code following track relay having associated therewith an impulse relay having normally released contacts movable to a picked up position in which they establish a circuit to supply energy to the rails of said first section, means responsive to release of the track relay contacts for supplying to said impulse relay energy effective to pick up the relay contacts momentarily, means including a back contact of said track relay for supplying energy to the rails of said second section, means including a front contact of said track relay for connecting a winding of a code following detector relay across the rails of said second section, said second section being equipped with track circuit apparatus effective when the section is vacant to supply to said detector relay over the section rails in the periods in which the detector relay is connected across the section rails energy to move the detector relay contacts from their first to their second position, an approach relay, a circuit governed by a contact of said detector relay for supplying energy to said approach relay, and means including a circuit governed by a contact of said impulse relay and controlling movement of the contact of said detector relay from its second to its first position.

3. In combination, a stretch of railway track including adjacent first and second track sections, said first section being equipped with coded track circuit apparatus including a code following track relay having associated therewith an impulse relay having normally released contacts movable to a picked up position in which they establish a circuit to supply energy to the rails of said first section, means responsive to release of the track relay contacts for supplying to said impulse relay energy effective to pick up the relay contacts momentarily, means including a back contact of said track relay for supplying energy to the rails of said second section, means including a front contact of said track relay for connecting a winding of

a code following detector relay across the rails of said second section, said second section being equipped with track circuit apparatus effective when the section is vacant to supply to said detector relay over the section rails in the periods in which the detector relay is connected across the section rails energy to move the detector relay contacts from their first to their second position, an approach relay, a circuit for sup-

plying energy to said approach relay when the contacts of said detector relay are in their second position, and means including a circuit governed by a contact of said impulse relay and controlling movement of the contact of said detector relay from its second to its first position.

4. In combination, a stretch of railway track including adjacent first and second track sections, said first track section being equipped with coded track circuit apparatus including a code following track relay having associated therewith an impulse relay having normally released contacts movable to a picked up position in which they establish a circuit to supply energy to the rails of said first section, means responsive to release

20 of the track relay contacts for supplying to said impulse relay energy effective to pick up the relay contacts momentarily, means including a back contact of said track relay for supplying energy to the rails of said second section, means

25 including a front contact of said track relay for connecting a winding of a polarized code following detector relay across the rails of said second section, said second section being equipped with track circuit apparatus effective when the

30 section is vacant to supply to said detector relay over the section rails in the periods in which the detector relay is connected across the section rails energy to move the detector relay contacts to their normal position, an approach relay, a

35 circuit including a normal polar contact of said detector relay for supplying energy to said approach relay, and a circuit including a front contact of said impulse relay for supplying energy to said detector relay to move its contacts to their reverse position.

40 5. In combination a stretch of railway track including adjacent first and second track sections, said first track section being equipped with coded track circuit apparatus including a code following track relay having associated therewith an impulse relay having normally released contacts movable to a picked up position in which they establish a circuit to supply energy to the rails of said first section, means responsive to release

45 of the track relay contacts for supplying to said impulse relay energy effective to pick up the relay contacts momentarily, means including a back contact of said track relay for supplying energy to the rails of said second section, means

50 including a front contact of said track relay for connecting a winding of a code following detector relay across the rails of said second section, said second section being equipped with track circuit apparatus effective when the section

55 is vacant to supply to said detector relay over the section rails in the periods in which the detector relay is connected across the section rails energy to pick up the detector relay contacts, a holding circuit for said detector relay including its own front contact and a back contact of said impulse relay, an approach relay, and means for energizing said approach relay when the contacts of said detector relay are picked up.

HERMAN G. BLOSSER.
